UNITED STATES PATENT OFFICE.

FRANK D. LINO, OF CHICAGO, ILLINOIS, ASSIGNOR OF TWO-THIRDS TO
PAUL B. LINO AND THOMAS S. QUINCY, OF SAME PLACE.

DESIGN FOR A GAME-BOARD.

SPECIFICATION forming part of Design No. 26,531, dated January 12, 1897.

Application filed September 8, 1896. Serial No. 605,195. Term of patent 3½ years.

To all whom it may concern:

Be it known that I, FRANK D. LINO, a citizen of the United States, residing at Chicago, Illinois, have invented and produced a new and original Design for a Game-Board, of which the following is a specification, reference being had to the accompanying drawings, in which—

Figure 1 is a plan view, and Fig. 2 a sectional view on line 2 2 of Fig. 1.

The leading feature of my design consists in a game-board having in its surface the irregular outlines shown in the drawings.

In the drawings, A represents circular grooves or depressions; B, radial channels; C, circular channels of less diameter, and D a central portion surrounded by the groove or

channel C. F and G represent channels or grooves, each continuous with one of the radial grooves B; H, I, and J, grooves arranged in triangular form and intersecting the grooves F and G, and K a groove connecting one of the outer circular grooves A with the apex of the grooves I and J.

L represents an enlarged termination of the channel or groove F, and M a like termination of the channel or groove G.

What I claim is—

The design for a game-board, substantially as herein shown and described.

FRANK D. LINO.
